(57) **CLAIM**

The ornamental design for a floating support for offshore wind turbine, as shown and described.

DESCRIPTION

FIG. 1 is a first perspective view of a floating support for offshore wind turbine showing my new design;

FIG. 2 is an enlarged perspective view thereof;

FIG. 3 is an enlarged front elevation view thereof;

FIG. 4 is a second enlarged perspective view thereof;

FIG. 5 is enlarged top plan view thereof;

FIG. 6 is a third enlarged perspective view thereof; and,

FIG. 7 is an enlarged bottom plan view thereof.

The broken lines shown represent environmental subject matter and form no part of the claimed design.
